UNITED STATES PATENT OFFICE

2,419,152

ELECTRICAL CONNECTOR

Karl J. Mosebach, Pittsburgh, Pa.

Application January 11, 1945, Serial No. 572,302

2 Claims. (Cl. 200—115.5)

1

My invention relates to electrical connectors and more particularly to those of the feeder tap type such as are employed in temporarily tapping trolley wires and the like for the utilization of electrical current for electrically-driven machines, welding apparatus, etc.

Such connectors or taps usually include fuses for the purpose of safety.

One object of my invention is to provide a connector device of the character referred to where-
in the fuses can be more readily placed and re-
placed than in the case of various types of con-
nectors or feeder taps heretofore employed, and
wherein no tools such as screw drivers, or
wrenches are required in the changing of the
fuses.

Another object of my invention is to provide a device of the character referred to, containing a fewer number of parts than are commonly employed.

Still another object of my invention is to pro-
vide a feeder tap that will engage a trolley wire
conductor more firmly than various types of taps
heretofore employed and which can conveniently
and safely be manipulated by the operator.

Some of the forms which my invention may
take are shown in the accompanying drawing
wherein Figure 1 is a longitudinal sectional view
through a connector, and Fig. 2 is a view showing
a modification thereof.

A connector comprises a tubular body or casing 3 of insulating material such as impregnated fabric or a molded plastic. A bushing 4 of simi-
lar insulating material has snug fit with one end of the tube 3 and is held against accidental dis-
placement by a series of pins 5. A cable 6 ex-
tends loosely through the bushing 4 and contains the usual conductor wires or wire 7 that extend through the end wall or bottom of a coupling
socket 8 that is screw-threaded to receive a cou-
pling plug 9, so that when the coupling plug is
screwed tightly into the socket, the ends of the
wires 7 will be firmly clamped or gripped. The
plug 9 has a stud-like extension 10 that extends into the hole in the end of the socket 8 to assist in holding the wires. The plug 9 also is provided with a skirt-like extension 11 that has a series of axially-extending slots 12 that are yieldable and will therefore serve as a holding clip for a
fuse 13.

At its other end, the tube 3 contains a threaded
bushing 14 that closely fits the tube and is
anchored therein by a series of tubular rivets 15.
An insulating-protecting sleeve 16 tightly en-

2

circles the tube 3 to cover the exposed ends of the rivets 15.

A screw-threaded plug 17 is detachably held in place by the bushing 14 and has a skirt portion slotted at various points as indicated at 18 so that it will serve as a holding clip for one end of the fuse 13 as in the case of the coupling plug 9.

The plug 17 has an extension 19 formed in-
tegrally therewith or rigidly attached thereto in
some other suitable manner. This member 19
serves as one of the gripping jaws for a trolley
wire 21 or other electrical conductor. A cooper-
ating jaw is shown at 22 and has a handle portion
23 that has an insulating covering 24. The jaw
22 is pivotally connected at 25 to the jaw 19. A
spring 26 yieldably holds the jaws in gripping
engagement with the conductor wire, and the
jaws have a series of grooves for gripping wires
of various thicknesses.

20 A disc 27 of insulating material is connected to the plug 17 by a screw 28 and serves to reduce danger of the operator's hand, when grasping the tube 3, from accidentally coming into engage-
ment with the jaw members. The disc or plate
27 has a slot at 29 to permit the handle 23 to be moved closely against the tube 3 when opening the jaws. It will be seen that when the tube 3 is held in the hand, the user's fingers or thumbs
25 can be moved against the handle at 24 to open the jaws when applying the tap to or removing it from a wire.

In connecting the device to the wires or wire
35 in the cable 6, the plug 17 is removed from the
tube and the coupling members 8 and 9 slid out
of the tube at its forward end, these members
being of slightly less external diameter than the
internal diameter of the bushing 14. There-
upon the cable 6 will be slid forwardly through
40 the bushing 14 and through the tube until it
projects from the forward end of the tube. Thereupon bared wires from within the cable
will be inserted into the socket member 8 and bent laterally. The plug 9 will then be screwed
45 tightly into the socket 8, by the use of wrenches,
thus firmly gripping the wire ends. The stud 10
will assist in gripping the wires in the hole at
the bottom of the socket and may also serve to
spread the wires. It will assist in the gripping
50 and holding action even though a single wire is
being clamped in the coupling members.

The cable 6 and the coupling can then be drawn to the position shown in Fig. 1, the fuse 3 inserted in the holding clips at 12, and the plug 17 screwed into place. When it is necessary to replace the

fuse, the plug 17 will be unscrewed, without the necessity of disturbing the coupling members 8-9.

Referring to Fig. 2, I show a plug 31 that serves substantially the same purpose as the plug 17, but instead of carrying a jaw, it is simply threaded to receive a wire-engaging hook 32. The hook could, of course, be welded or otherwise secured to the plug.

I claim as my invention:

1. An electrical connector comprising a tubular body having one end partly closed by a bushing through which a cable conductor may extend, a screw-threaded bushing secured in the other end of the tube, a screw plug removably engaging the latter bushing, means carried by the plug, for detachably engaging an electrical conductor, a fuse-holding clip carried by the inner end of the plug, a screw-threaded coupling socket of smaller external diameter than the screw-threaded bushing, having abutting engagement with the inner edge of the first-named bushing and having a hole through its end wall, through which wires from the cable may extend, and a coupling plug having threaded engagement with the coupling socket and having a fuse-holding clip, and a fuse carried by the clips, the coupling plug serving to clamp wires against an inner wall surface of the coupling socket, and the coupling members being removable from the tubular body, when the first-named plug is removed.

2. An electrical connector comprising a tubular body having one end partly closed by a bushing through which a cable conductor may extend, a

screw-threaded bushing secured in the other end of the tube, a screw plug removably engaging the latter bushing, means carried by the plug, for detachably engaging an electrical conductor, a 5 fuse-holding clip carried by the inner end of the plug, a screw-threaded coupling socket of smaller external diameter than the screw-threaded bushing, having abutting engagement with the inner edge of the first-named bushing and having a 10 hole through its end wall, through which wires from the cable may extend, a coupling plug having threaded engagement with the coupling socket and having a fuse-holding clip, a fuse carried by the clips, the coupling plug serving to 15 clamp wires against an inner wall surface of the coupling socket and the coupling members being removable from the tubular body, when the first-named plug is removed, and a stud on the coupling plug, in position to extend into and partly 20 fill the hole in the coupling socket.
